UNITED STATES PATENT OFFICE.

ANDRIAN J. BARANOFF, OF LOS ANGELES, CALIFORNIA.

COMBINATION TUBE EXPANDER, BEADER, AND CUTTER.

Application filed December 1, 1922. Serial No. 604,412.

To all whom it may concern:

Be it known that I, ANDRIAN J. BARANOFF, a citizen of the United States, residing at Los Angeles, in the county of Los Angeles and State of California, have invented new and useful Improvements in Combination Tube Expanders, Beaders, and Cutters, of which the following is a specification.

My invention is a hammerless combination tube expander, beader and cutter, particularly useful for expanding and beading a tube, for securing the end of the tube in an opening in a plate, and for cutting the tube the proper length from said plate.

The main object of my invention is to provide a device of this character which will be simple in construction and practical and efficient in operation.

Other objects and advantages will appear hereinafter and while I show herewith and will describe a preferred form of construction, I desire to be understood that I do not limit myself to such preferred form, but that various changes and adaptations may be made therein without departing from the spirit of my invention as hereinafter claimed.

One form of my invention is illustrated in the accompanying drawing in which:

Fig. 1 is a vertical longitudinal section of my invention and a tube and plate, with my invention in position in said tube ready to form the bead on the end of the tube against the top of the plate and to expand the tube against the under side of the tube to secure the end of the tube in the aperture in said plate.

Fig. 2 is a view similar to Fig. 1 but with my invention in position after having formed the bead on the tube and having expanded the tube.

Fig. 3 is a bottom plan view of the beader.

Fig. 4 is a cross section of my invention taken on line 4—4 of Fig. 1 showing the expanders.

Similar reference characters refer to similar parts throughout the several views.

In the drawing is shown a plate A, provided with an aperture a, and a tube B, one end of which being fitted in said aperture and projecting slightly above said plate.

My invention consists primarily of a spindle C, an expander D, a beader E, and a cutter F. The spindle C extends through a tubular member 1 and has an external thread 2 on its upper portion which engages an in-

ternal thread 3 in the upper part of said support whereby said spindle when turned one way or the other is moved up or down within said support. On said spindle at a distance below thread 2 is formed a conical cam 4, the base of which is larger in diameter than the spindle, and it tapers downwardly to the diameter of the spindle. The portion 6 of the spindle between the thread 2 and the cam 4 is square and is smaller in diameter than the upper threaded part of the spindle. The beader E includes a head 7 and beader rollers 8, preferably four in number. Said head has a central square opening 9 through which extends the spindle square portion 6. A coil spring 10 surrounds the square portion 6 of the spindle within the tubular member 1, bearing at its lower end on the head 7 and at its upper end against a shoulder 11 at the lower end of thread 2, said spring forming a cushion for the beader and normally urging the beader head downwardly against the upper part of cam 4. The beader head has an upstanding sleeve 7^a which slides on the lower portion of the tubular member 1. The beader rollers 8 are journaled in brackets 12 depending from the lower side of the beader head 7; said brackets being dovetailed at their upper ends to engage corresponding radial grooves 12^a in the under side of the beader head 7 whereby the rollers may be moved in and out to engage tubes of different diameters.

A nut 13 screws on the upper end of the thread 2 and is secured on the upper end of tubular member 1. The upper end 14 of the spindle O is square to receive the chuck of a motor G for turning same. The lower end portion 15 of the spindle is square and the portion 16 of the spindle between said lower end portion and the cam 4 is provided with a thread 17. A nut 18 screws on the thread 17, on the upper end of which nut are formed a plurality of upstanding arms 19 spaced equidistant apart around the nut. To the upper ends of the arms 19 are connected one end of links 20 respectively. A plurality of expanding dies 21 fit close together around the spindle, bearing at their upper ends against the cam 4 and provided respectively with slots 22 to receive the other ends respectively of the links 20, which ends are connected respectively to said dies.

The dies 21 have expanding surfaces 23 on their lower ends on the outer sides thereof

for engaging and expanding the tube B. The nut 18 is provided with an external thread 24 on which screws a split nut 25, the sections of which nut are secured together by 5 bolts 26. The split nut 25 is formed with an internal annular flange 27 at its lower end on which flange rests an external annular flange 28 on the upper end of the cutter cone 29, whereby said cone is supported 10 by said nut; said cone being provided with a longitudinal square bore 30 through which extends the lower square portion 15 of the spindle C. The cone 29 is provided with a plurality of longitudinal dovetailed grooves 15 31 and the cutter knives 32 are dovetailed at their inner ends to engage said grooves, there being a ring 33 surrounding said cone provided with slots 34 through which said knives extend; the outer ends of said knives 20 being edged to cut the tube B.

The operation of my invention is as follows: The lower portion of the spindle, together with the cutter and expander are placed within the tube B with the rollers 8 resting on the upper edge of said tube. A motor G is applied to the upper square end 14 of the spindle, by means of which motor said spindle is rotated and pushed further into the tube B compressing spring 10, during which operation the nut 18 moves upwardly on the spindle thread 17 together with the nut 25 and cutter F, and the dies 21 are forced outwardly by the cam 4, expanding the tube at the under side of plate A 30 (Fig. 2), while the beader is rotated and the spring 10 expanded, forcing the beader downwardly and causing the beader rollers 8 to turn over the upper edge of the tube B against the upper side of plate A, thus beading the tube, after the tube is expanded, and firmly securing the end of the tube in said plate. As the cutter moves upwardly the rotating cone 29 forces the rotating knives 32 outwardly which cuts off the tube the desired length. The rotation of the spindle is 35 then reversed, which causes the nuts 18 and 25 and cutter cone 29 to move downwardly and allows the expanding dies 20 and the cutter knives 32 to move inwardly, whereupon the device may be withdrawn upwardly 50 from the tube B. The tension and cushion of the spring 10 may be adjusted by turning the nut 13 together with the tubular member 1.

Having described my invention, what I 55 claim as new and desire to secure by Letters Patent is:

1. In a device as disclosed, a spindle, an expander mounted on said spindle for expanding the tube when the spindle is rotated and forced into the tube, a beader on said spindle for beading said tube when it is expanded, and a cutter including a cone mounted on said spindle to rotate therewith and to move upwardly thereon as the spindle is rotated and forced into the tube, and knives mounted on said cone to be forced outwardly and rotated by said cone when the cone is rotated and moved upwardly by the spindle. 60
2. In a device as disclosed, a spindle, an expander comprising a nut screw seated on said spindle, expanding dies, means connecting said nut and said dies, and a cam on said spindle for engaging said dies and forcing them outwardly together with the action of said nut moving upwardly on the spindle as the spindle is rotated and forced into the tube; a beader mounted on the spindle for beading the end of the tube, and a cutter for cutting off the expanded and beaded tube the desired length, said cutter comprising a cone mounted on said spindle to turn therewith and to move longitudinally thereon, means for rotatably connecting said cone to said nut, and knives mounted on said cone to be rotated and forced outwardly by said cone when the cone moves upwardly with said nut. 65

ANDRIAN J. BARANOFF.
